UNITED STATES PATENT OFFICE.

WARREN B. FLANDERS, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE GOVERNOR

Application filed September 4, 1920. Serial No. 408,183.

To all whom it may concern:

Be it known that I, WARREN B. FLANDERS, a citizen of the United States, and a resident of Essington, in the county of Delaware and 5 State of Pennsylvania, have invented a new and useful Improvement in Turbine Governors, of which the following is a specification.

My invention relates to governing mechanism for steam turbines, and has for its 10 object the provision of a governor in the form of a centrifugal pump having speed responsive valve means to render the pump operative, said pump being adapted to increase the resistance to rotation of the 15 turbine spindle and thereby prevent overspeeding of the latter.

I attain this object by means of the mechanism illustrated in the accompanying drawings in which—

Figure 1 is an end elevation of a portion of the turbine rotor with the governing mechanism attached; Figure 2, a sectional view through the rotor and governing mechanism; Figure 3, an end elevation of a modification of my invention; Figure 4, a side elevation of the modification of my invention shown partly in section; and Figure 5, a sectional view through one of the valves 30 of the modification.

Referring to the drawing for a more detailed description of my invention, I indicate in Figures 1 and 2 a single stage impulse wheel 10 mounted on a turbine shaft 11. Mounted adjacent to and coaxially with the impulse wheel 10 is a hub or drum member 12 provided with a diametral recess 13 with its axis substantially normal to the axis of the turbine shaft. The ends or outlets of the recess 13 are beveled at 14 and 15 to provide valve seats for the valve covers 16 and 17. A helical spring 18 within the recess 13 is provided with straight tips 19 and 20 which project through axial holes in the covers and are threaded to receive nuts 21 and 22 which serve to retain the valve covers in contact with the valve seats 14 and 15. By turning the nuts 21 and 22 the tension of the spring 18 may be readily adjusted. An axial passage 23 in the drum serves as means

of communication between the exterior of the drum and the recess within.

In the modification of my invention as shown in Figures 3 and 4, a single stage impulse wheel 30 is mounted on a turbine shaft 55 in a similar way to that shown in Figure 2 and is provided with a hollow drum 32 open at the end. A series of ports or fluid transferring passages 33 are spaced around the periphery of the drum and serve as means 60 of communication between the exterior and interior thereof. The end of the drum is closed by an end piece or cover 34 provided with a series of lugs or tongues 35 which extend normally to the end piece and which 65 fit snugly over the outside of the drum. These tongues serve to hold in place a series of leaf springs 36 which act as valve covers for the ports 33 spaced around the periphery of the drum. An axial passage 37 in the 70 end piece or cover serves as means of communication between the exterior of the drum and the interior thereof.

In Fig. 5 is shown a detail of the spring valve, the section shown being taken through 75 one of the ports 33 spaced around the periphery of the drum 32. To close the port 33 and thereby shut off communication between the exterior and interior thereof, a leaf spring 36 is provided which acts as a 80 valve cover for the port 33. The leaf spring 36 is held in place by means of the tongue 35 which is an integral part of the end piece or cover 34 and projects normally therefrom. The drum should be provided with a 85 small recess and the tongue with a like projection in order to hold the spring firmly in place as shown.

It is a well known fact that when part of the load on a turbine is removed, the speed 90 of the turbine will increase if some governing means is not provided, and serious damage to the turbine may be the result of the overspeeding. The governing mechanism as herein described acts as a centrifugal pump 95 which imposes a temporary load on the turbine when a predetermined overspeed is reached.

The operation of my improved device is as follows: when the turbine is running at 100

normal speeds the force exerted by the spring 18 will be sufficient to overbalance the centrifugal force acting on the valve covers 16 and 17, and the valve covers will therefore be firmly held against the valve seats 14 and 15 at the ends of the recess within the drum. When a predetermined overspeed is reached, the centrifugal force acting on the valve covers 16 and 17 will overbalance the force of the spring 18 and the covers will be lifted from the valve seats. As the impulse wheel of the turbine is running in the exhaust chamber of the turbine, exhaust steam will enter the drum through the passage 23 and will be forced out at the ends of the passage due to the centrifugal force acting thereon. The drum therefore acts as a centrifugal pump taking in steam at its axis and exhausting it at its periphery. This pumping action will impose a load on the turbine to make up for the loss in exterior load and will prevent the turbine from overspeeding. When the exterior load is again imposed on the turbine, the speed will be reduced until the force of the spring again overbalances the centrifugal force on the valve covers causing them to close. The temporary load due to the centrifugal pumping action will then be removed, and the turbine will again operate under normal conditions.

In the modification of my invention when the turbine reaches a predetermined overspeed, the centrifugal force acting on the leaf springs 36 will cause them to uncover the ports 33 arranged around the periphery of the drum 32. Steam will then enter the drum from the exhaust chamber through the passage 37 and will be discharged outwardly through the ports 33 around the periphery of the drum. As in the previous case the drum acts as a centrifugal pump taking in steam at the axis and forcing it out at the periphery, thereby imposing a load on the turbine. When the exterior load returns to the turbine, the speed of the turbine will be reduced until the leaf springs again cover the ports 33. The temporary load will thereby be removed, and the turbine will again operate under normal conditions.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. In combination with a rotating element of a fluid turbine, governing means therefor comprising a centrifugal fluid

transferring means and speed responsive means to control the operation of the fluid transferring means, said governing means and speed-responsive means being carried by the rotating element.

70

2. In combination with a rotating element of a fluid turbine, governing means therefor comprising a centrifugal fluid transferring means and spring retained speed responsive means to control the operation of the fluid transferring means, said governing means and speed-responsive means being carried by the rotating element.

75

3. In combination with a rotating element of a fluid turbine, governing means therefor comprising a drum element adjacent to and coaxial with the rotating element having fluid transferring ports in the periphery and means responsive to the speed of rotation of the rotating element for uncovering the ports, said means responsive to the speed of rotation of the rotating element being carried by the rotating element.

80

4. In combination with a rotating element of a fluid turbine, governing means therefor comprising a drum element adjacent to and coaxial with the rotating element having fluid discharging ports in the periphery thereof, and spring retained means responsive to the speed of rotation of the rotating element for uncovering the ports, said governing means and means responsive to the speed of rotation of the rotating element being carried by the rotating element.

85

5. In combination with a rotating element of a fluid turbine, governing means therefor comprising a drum element adjacent to and coaxial with the rotating element having fluid discharging ports in the periphery thereof, and spring retained means responsive to the speed of rotation of the rotating element for uncovering the ports, said governing means and means responsive to the speed of rotation of the rotating element being carried by the rotating element.

90

6. In combination with a rotating element of a steam turbine, governing means therefor comprising a drum member adjacent to and coaxial with the impulse element having a diametral recess and an axial passage communicating between said recess and the exterior of the drum, covers adapted to close the ends of the recess, and spring means within the recess for retaining the covers, said covers adapted to uncover the ends of the recess due to centrifugal force acting thereon when a predetermined overspeed is reached.

100

7. The combination with a rotating wheel of a steam turbine, governing means therefor comprising a drum member mounted coaxially with and adjacent thereto and having a diametral recess the axis of which is substantially normal to the axis of rotation and an axial passage communicating between the exterior of the drum and the interior thereof, covers adapted to close the ends of the recess, and spring means for maintaining the covers closed, said covers being responsive to the speed of rotation of the turbine spindle to uncover ends of said recess.

105

8. The combination with a rotating element mounted within a body of fluid, of speed-responsive means carried by said rotating element, said speed-governing means

110

115

120

125

130

comprising a drum member with spring-retained valves and passages for setting up a centrifugal pumping action above a pre-determined speed of the rotating element.

5 8. The combination with a rotating element of a fluid turbine, of speed-governing mechanism carried by said rotating element and mounted within the exhaust chamber of said turbine, said governing mechanism

comprising a drum member having fluid discharging ports in the periphery thereof and spring-retained means responsive to the speed of rotation of the rotating element for uncovering the ports.

In testimony whereof, I have hereunto 15 subscribed my name this 25th day of August, 1920.

WARREN B. FLANDERS.
